UNITED STATES PATENT OFFICE.

WILLIAM G. BETZ, OF BUFFALO, NEW YORK, ASSIGNOR TO STRAUER PIANO COMPANY, OF HAMMOND, INDIANA, A CORPORATION OF INDIANA.

PNEUMATIC ACTION FOR PIANOS.

1,335,476.

Specification of Letters Patent. Patented Mar. 30, 1920.

Original application filed May 8, 1914, Serial No. 837,130. Divided and this application filed June 1, 1916.
Serial No. 101,145.

To all whom it may concern.

Be it known that I, WILLIAM G. BETZ, a citizen of the United States of America, residing in Buffalo, county of Erie, and State of New York, have invented certain new and useful Improvements in Pneumatic Actions for Pianos, of which the following is a specification.

My invention relates to pneumatic actions for pianos, the present application which is a division of my application filed May 8th, 1914, Serial No. 837,130, Patent No. 1197596, being directed more particularly to action operating mechanism. One of the principal objects of the present invention is to provide an improved construction for hanging or supporting, and regulating, action levers whereby such levers and supporting arms are preferably individually removable. In pneumatic actions a bellows for each hammer action is ordinarily provided and connecting links or levers are used for connecting the bellows and hammer actions. It is of advantage to be able to regulate the stroke of the bellows or connected levers and by my improved construction I support the connecting link or lever by individually removable arms which also carry adjusting means for regulating the stroke of the bellows and connected levers.

I will now refer to the accompanying drawing for a better understanding of my invention in which like reference characters indicate like parts and in which—

Figure 1 is a sectional view illustrating the control mechanism of one key;

Fig. 2 is a face view of one valve mechanism with the cover of the air chamber removed;

Fig. 3 is a side elevation of a valve lever;
Fig. 4 is a left side view of Fig. 3;

Fig. 5 is a detail view of a combined valve lever support and valve seat; and

Fig. 6 is a sectional view through the center of Fig. 5; and

Fig. 7 is a plan view of a portion of Fig. 1 showing the preferred method of independently mounting the action levers and lever-supporting arms.

In the preferred embodiment of my invention as illustrated, I provide a so-called air chest or chamber A, comprising preferably vertically disposed facing walls 1 and 2 having spacers as 3, 4, the cap or wall 2

being attached by screws 5 so that it may be readily removed. This chamber A is, of course, of such length and width as to suitably take care of the desired number of valve mechanisms, as will be readily understood.

A single valve mechanism B is shown comprising a plate 6 having a centrally disposed air port 7 formed so as to provide a valve seat 8, and above said port a pair of inwardly projecting ears 9 are formed, having concave formations 10 for supporting the valve lever shaft. Plate 6 is secured to the inner surface of the wall 1 preferably by screws 11, the valve seat 8 projecting into a chamber 12 having a valve seat 13, said chamber 12 having an atmosphere duct 14 and bellows duct 15.

A valve lever 27 is provided, having a pointed shaft 28, which is sprung between the resilient arms 9 and held between the concaved portions 10 in such a manner that the depending lever 27 is free to reciprocate without any lateral movement, thus doing away with guides, such as have been previously used.

At the free end of lever 27, a valve gate 29 is adjustably attached by means of a screw 30, said valve gate having facings preferably of leather, which act upon valve seats 8 and 13.

At a point preferably intermediate of the pivoted end of lever 27 and the valve support 30, a buffer 31 is adjustably secured, said buffer co-operating with a diaphragm 32, which is preferably of rubber or leather, and suitably fastened over the diaphragm actuating chamber 33. Chamber 33 is preferably round, and a duct 34 leads therefrom to a tube 35 extending to its tracker bar port 36. A connecting duct 37 leads from the main air chamber A to each duct 34, there being a cap 38 provided with a small opening inserted in each duct 37 to allow only a small flow of air. A tube from chamber A is also connected to the vacuum pump to create a vacuum in chamber A in a well-known manner.

It will, of course, be understood that in using my invention, the air chest is made wider than shown, and the associated bellows and valve mechanisms are staggered in accordance with well known practice.

An action-operating bellows C is suit-

ably fastened to the wall 1 in connection with duct 15 and is connected to a hammer action lever 16 by means of a connecting rod 17, which is pivotally attached at its 5 upper end and held to the bellows extension 18 by a pair of ball faced nuts 19.

Each action lever 16 is pivotally secured to an individual arm 20, which is detachably secured to a rail or bar 21 preferably 10 by means of screws 22, said rail being suitably supported, preferably by screws 23. An overhanging portion 20¹ of arm 20 carries an adjustable stop 24, whereby the upward travel of action of lever 16 is determined. An adjustable buffer screw 26 is 15 also carried by lever 16, which lever acts upon the action mechanism D, as will be readily understood.

Each action lever 16 and its supporting 20 arm being individual units it will be apparent that they may be readily detached or replaced without disturbing others.

In the operation of the action, a vacuum 25 is created in the air chamber A by suitable means, and with the music sheet covering the duct 36 a vacuum is also created in duct 34. Thus the atmospheric pressure against valve 29 tends to hold valve lever 27 in its 30 normal or inoperative position, and therefore the bellows C is maintained open. Upon opening tracker port 36, duct 34 tends to come up to atmospheric pressure, resulting in a pressure against diaphragm 32 by the pressure in chamber 33. Buffer 31 therefore 35 acts upon lever 27, which causes valve gate 29 to leave its normal or air chamber port seat and engage the atmosphere duct seat 13, whereby the bellows chamber is connected to the chamber A by duct 15. A 40 vacuum is thus created in the bellows chamber, allowing the atmospheric pressure to close the bellows, whereby the arm 18 is raised and through connecting rod 17 and lever 16 the hammer action mechanism D 45 is actuated.

Upon closure of port 36 again, duct 35 and chamber 33 being connected to chamber A again have the pressure therein reduced so that the atmospheric pressure acting upon 50 valve 29 through duct 14, forces the valve gate 29 against its seat 8 and thus the bellows chamber being connected to atmosphere through ducts 15, 14, again opens and restores the action mechanism D.

55 Although in illustrating my invention I have chosen a preferred form, it is to be understood that it may be applied to other arrangements; neither do I desire to be limited to the construction shown as changes 60 and modifications will readily occur to those skilled in the art, and I aim to cover all those changes and modifications as come

within the spirit and scope of the appended claims.

Having described my invention, what I 65 claim as new and desire to secure by United States Letters Patent, is;

1. A pneumatic action for pianos comprising a horizontal rail, action-levers, adjacently-positioned, independently-removable lever-supporting arms carried by said rail, means for individually connecting each lever-supporting arm with an associated action-lever, and an adjustable stop 70 independently supported by each arm for 75 limiting the length of the stroke of the corresponding action-lever.

2. A pneumatic action for musical instruments comprising a horizontal rail, action-operating bellows below the rail and 80 extending transversely thereof, a horizontally-disposed action-lever positioned above each bellows lying longitudinally thereof and operatively connected thereto, independently-removable lever-supporting arms 85 secured to said rail each pivotally supporting one of said action-levers, an extending portion individual to each of said arms overhanging the corresponding lever, and an adjustable stop carried by each of said extending portions for controlling the travel 90 of the corresponding arm.

3. A pneumatic action for musical instruments comprising a horizontal rail, lever-supporting arms independently and 95 detachably secured at one end to the rail and projecting laterally therefrom, an action-lever for each arm having one end pivotally attached to an intermediate portion of the arm whereby an extending portion of the 100 arm is positioned adjacent an intermediate portion of the lever, and adjusting means for regulating each lever carried by the extending portion of the associated arm.

4. A pneumatic action for musical instruments comprising a supporting rail, straight rectangular elongated lever supporting arms independently and detachably secured at one end to a horizontal side of the rail and projecting laterally therefrom, an action-lever for each arm having one end pivotally attached to an intermediate portion of the arm whereby the free extending portion of the arm is positioned adjacent an intermediate portion of the lever, and adjusting 110 means for regulating each lever carried by the extending portion of the associated arm.

Signed by me at Chicago, county of Cook and State of Illinois, in the presence of two witnesses.

WILLIAM G. BETZ.
